ELECTRIC HEATING PLATE

Etienne Challet, Paris, France, assignor of one-fourth to "Enterprises Electriques Fribourgeoises," Fribourg, Switzerland

Application October 29, 1938, Serial No. 237,733
In Switzerland November 4, 1937

3 Claims. (Cl. 219—37)

The present invention has for its object an electric heating plate comprising at least two concentric parts which are adapted to be arranged at different levels, according to Swiss Patent No. 193,023, said invention being further characterized by the fact that each of the concentric parts is formed by at least one torus, the cross-section of each of said parts being so shaped that it enables contact to be made with the bottom of a deformed receptacle, along a circular line located as near as possible to the zone where the density of heating of said part is at a maximum.

In a first embodiment, each part is formed by a single torus of circular or oval cross-section which may or may not be flattened, that is to say which has a more or less pronounced flattened portion at the upper part thereof.

In a second embodiment, the cross-section of the single torus forming each part is shaped like an elongated bean, the convexity of which is turned upwards.

In a third embodiment, each part is formed by a group of tori, three for example, the tori forming each part occupying an invariable position relatively to each other, said tori being contiguous or not and of circular or oval cross-section, it being possible for the upper envelope curve of the tori of the same part to be independent or to belong to the same tubular spiral.

Preferably, abutments may be provided for the inner parts of smaller diameter, so that under the weight of a receptacle of small diameter, which does not rest on the outer part of the plate, the inner part of the plate is not pushed right in.

The accompanying drawing shows diagrammatically and by way of example, cross-sections of a number of embodiments of the plate according to the invention, Figs. 1, 2 and 6 being elevational views in cross-section of three embodiments of the hot plate and Figs. 3, 4 and 5 being cross-sectional views showing the various shapes each heating element torus can assume.

Fig. 1 relates to a first embodiment comprising two concentric parts 1 and 2 each formed by a single torus of circular cross-section. The inner part 2, in the inoperative position, is urged by springs 3 in such a manner as to be higher than the part 1. The latter is supported by supports 4. Abutments 17 limit the inward movement of the part 2 under the weight of a receptacle of small diameter. The top of said abutments 17 is located at such a height that it is a small

amount d' lower than the lower part of 1, so as to allow of an efficient contact with a deformed receptacle having a convex bottom. The relative positions of the parts 1 and 2 will therefore be automatically determined by the shape of the bottom of the receptacle that is placed on the plate, the inner part being higher if the bottom of the receptacle is concave, or on the contrary being lower if the bottom of the receptacle is convex, the parts being on the same level if the bottom of the receptacle is flat.

It will be observed on the other hand that the cross-section of the torus forming each of the parts is of such a shape that it enables contact to be obtained with the bottom of a deformed receptacle along a circular line which is as near as possible to the zone where the density of heating of said part is at a maximum.

Fig. 2 shows an embodiment of the same type but having three parts 5, 6 and 7 which are successively higher relatively to each other when there is no receptacle on the plate, each part being likewise formed by a single torus. The part 7 is supported by springs 9; the part 6 is supported by springs 8, whereas the part 5 rests on fixed supports 10. This embodiment has the same properties as the embodiment of Fig. 1.

Instead of having a circular cross-section, the tori forming the various parts of the various embodiments could have a cross-section shaped like a circle which is slightly flattened at the top and at the bottom, as the cross-section 11 of Fig. 3, or an oval cross-section such as the cross-section 12 of Fig. 4, or finally an elongated bean-shaped cross-section, the concavity of which is turned downwards, such as the cross-section 13 of Fig. 5.

Fig. 6 relates to another embodiment in which each part 14 and 15 is formed by three tori that occupy invariable positions relatively to each other, the central torus of each part being higher than the two adjacent tori, that is to say that the envelope curve at the upper portion in each part is of convex shape. The central torus of the part 15 is a small amount, d , higher than the central torus of the part 14. The part 14 rests on fixed supports 18, whereas the part 15 rests on springs 16.

Of course, the number of parts is not limited to two and the number of tori in each part is not limited to three. Finally, the tori of the same part may be contiguous or not, and may be independent of each other or belong to the same tubular spiral. It will furthermore be observed

that the plate shown in Fig. 6 also has the properties attributed to the plate of Fig. 1.

The supporting springs could be replaced by equalizing arrangements, as is the case for certain of the plates described in the aforesaid Swiss patent.

I claim:

1. An electric heating plate comprising a plurality of concentric parts, means permitting said parts to move relative to one another to insure a shape-conforming engagement with the bottom of a vessel placed on said plate and each of said concentric parts constituting a plurality of tori forming a set of tori having a cross section defining a convex upper envelope curve.

2. An electric heating plate comprising a plurality of concentric parts, means permitting said parts to move relative to one another to insure a shape-conforming engagement with the bottom

of a vessel placed on said plate, each of said concentric parts constituting a plurality of tori forming a set of tori having a cross section defining a convex upper envelope curve, and each set of tori containing only one continuous resistance coil.

3. An electric heating plate comprising a plurality of concentric parts, means permitting said parts to move relative to one another to insure a shape-conforming engagement with the bottom of a vessel placed on said plate, each of said concentric parts constituting a torus with a convex upper surface so that contact may be made along a circular line with a deformed bottom of a vessel placed on said plate, and abutments for limiting said relative movement of said parts.

ETIENNE CHALLET.
